S. H. FURRY

SIGN

Filed May 16, 1921

UNITED STATES PATENT OFFICE.

SAMUEL H. FURRY, OF LANCASTER, OHIO.

SIGN.

Application filed May 16, 1921. Serial No. 470,118.

To all whom it may concern:

Be it known that I, SAMUEL H. FURRY, a citizen of the United States, residing at Lancaster, in the county of Fairfield and State 5 of Ohio, have invented certain new and useful Improvements in Signs, of which the following is a specification.

This invention appertains to certain improvements in signs generally, and more particularly to a type of the same adapted for 10 use as a railroad crossing signal sign, and capable of being controlled from a distance, as from a moving car or train.

The principal object of the invention is 15 to provide for a signal sign of the class mentioned, and one embodying, in addition to the usual words of warning as now used on railroad crossing signs and which must be read by pedestrians or operators of road 20 vehicles, certain movable and audible signals to be actuated from the oncoming train at a distance from a particular crossing, and which will be continuously actuated until the train has reached and passed the crossing. 25

Another object of the invention is to provide for an electrically operated warning sign of the type mentioned, and one embodying certain novel features of construction 30 and arrangement of parts whereby, while being particularly designed for use as a railroad crossing signal or warning sign, the same is capable of a more general use, especially for general advertising purposes, 35 and, in the use thereof as a railroad crossing signal sign, it is adapted to be operated from any of the known forms of track signal circuits under the control of the engineer or motorman of either steam or electric rail- 40 way systems.

With the foregoing and other objects in view, the invention resides in the certain novel and useful construction and arrangement of parts as will be hereinafter more 45 fully described and illustrated in the accompanying drawings, and set forth in the appended claims, in which:

Fig. 1 is a front elevation of the sign per- 50 se,

Fig. 2 is a fragmentary vertical trans- 55 verse section taken on the line 7—7 of Fig. 1.

Fig. 3 is a fragmentary section taken on the line 8—8 of Fig. 1.

Fig. 4 is a rear elevation of a modified 55 form of the interchangeable letters used on the sign,

Fig. 5 is an edge view of the latter.

Referring to the drawings, wherein similar characters of reference designate corresponding parts in the several views thereof, the improved sign comprises a frame 10, preferably formed of heavy strap iron bent into substantially rectangular or oblong form, having its opening closed by a sheet of 60 fabricated material 11, preferably of wire of any suitable or desired mesh, and secured to the sheet 11, to one or both sides of the same, are readable words of warning such as are now employed on known forms of 65 railroad crossing signs. These readable words of warning are preferably arranged as follows:—Beginning at the top of the sheet 11, and horizontally thereof as shown in Fig. 1, the first line comprises the words “Double 70 track”; the second line “Railroad crossing”; the third line, “Warning” in larger letters than that used in the first two lines of the wording; and the fourth line, “Stop-Look-Listen”. The words “double track” are used 75 only when the sign is to be used at the crossing of a double tracked railway, and the word “single” will be substituted for the word “double”, when the sign is to be used on a single tracked railway, or, in the latter instance, the reference to the type of track 80 may be eliminated entirely. The letters, from which the words are to be formed, when assembled on both sides of the sheet 11 of the sign, are to be constructed of sheet 85 metal, preferably cut to form substantially rectangular plates 12, on one side of which the individual letters of the alphabet are to be printed, embossed, or otherwise applied thereto.

In this instance, the rear faces of the complementary letter plates 12, to be positioned on the opposite sides of the sheet 11 of the sign, will be opposed one to the other with the sheet 11 between the same, and clamped in registry one with the other by 90 means of suitable fastenings, preferably in the form of screws or bolts 13 being passed through sets of alining openings 14, formed in the plates 12 for the purpose. When only 95

one side of the sheet 11 is to be provided with the words of warning, or advertising matter as the case may be, similar lettered plates 12', as shown in Figs. 9 and 10, will be used, 5 and the same are to be held in proper position on the sheet 11 by means of fastenings, such as spring clips or the like 15 carried on the rear faces of the plates, and adapted to engage over the wire section forming the 10 base of the sheet. In any case, the several letters of a line of wording are properly aligned one with respect to the other by having all of the fastenings of the same engaging the aligned mesh openings of the sheet 15 11 of any particular horizontal line of such mesh openings.

For use at night, the sign is preferably illuminated, as shown, and by means of a suitable number of electric lamps (not 20 shown) carried in a reflecting housing 16, which is supported medially of the upper side bar of the frame 10, the reflector housing being arranged to throw the light beam from the same downwardly of one or both 25 side faces of the fabricated sheet 11 of the sign, and, if necessary, two of these lamp housings may be provided, one at opposite sides of the sign. The lamps of the housing, or housings, 16 are preferably lighted 30 from a local source of current supply (not shown).

In the use of the sign, thus constructed and arranged, at railway crossings, the same is adapted to be suspended to one side of the 35 railroad track and directly over and crossways of the intersecting roadway. Current is led to the lamps of the housings 16 by means of a conductor 23, and by a conductor 24 leading to a control switch, not shown. 40 The conductors 23 and 24 communicate with a suitable source of electrical energy. The switch may be located at any desired point for the cutting on and off of the lights.

The preferred embodiment of the sign is 45 to be provided with both audible and visual signal devices, and for such purpose, the wire mesh sheet 11 is cut away centrally inward of the lower side thereof to provide a semi-circular opening 27 having its edges 50 secured to a similarly shaped frame 28, also of strap iron or the like, and formed medially of the upper horizontal side of the frame 28 is a transversely disposed bearing 29, in which is journaled the shaft or spindle 55 30 of a signal arm 34, which is arranged to be oscillated within the opening to either side of its normally vertical depending position, through the medium of a pitman rod 31 connecting the same, as at 32, to a large 60 gear 33 arranged in mesh with a small gear or pinion 35, carried at one end of the shaft of a small electric motor 36 connected with a suitable source of electrical energy, gears 33 and 35 and the electric motor 36 are supported at one of the lower corners of the sign 65

frame 10 and suitably secured in position thereon and within a protecting housing 37. The signal arm 34 is preferably in the form of a semaphore signal, such as are now commonly used for railroad signalling systems, 70 and the same is to be provided with an opening inwardly of its lower end for the reception of an electric lamp 41 to be inclosed between colored (red) lenses 41' disposed at the opposite sides of the openings. Current is led from the lighting circuit conductors 23 and 24, by conductors 42 and 43, respectively to a pair of contact fingers 44 and 45, carried on a bracket arm 46 extending inwardly of the bearing 29, and which are arranged to bear on a pair of contact rings 47 carried on and insulated from the shaft 30 of the signal arm 34. Conductors 49 and 50 lead from the contact rings 47 and 48 to the lamp 41 at the lower end of the 80 arm 34.

Located in the opposite lower corner of the sign frame 10, is an audible signal device 51, preferably in the form of an electric bell, and the latter is connected in circuit with the motor, by a suitable conductor not shown. The circuit being closed in any suitable manner or from any suitable point, the motor is drawn into operation whereby the signal arm is oscillated and at the same time the audible signal which is in circuit with the motor will be sounded.

It is well understood that, while the invention has been described and illustrated herein in specific terms and detail of construction, arrangement and assembly of parts, various modifications and changes in the same may be resorted to without departing from the spirit of the invention, or the scope of the claims appended hereto.

Having thus fully described the invention, what is claimed is:-

1. A sign comprising a rectangular open frame, a foraminous sheet arranged to close the opening formed by said frame, letters carried by each side of said sheet to provide each side with a caution indication, means for illuminating said indications, and electrically operated audible and visual signaling devices supported by the frame for directing attention to said indications, said means for illuminating said indications being independent of said letters, said sheet having openings for said signaling devices.

2. A sign comprising a foraminous element, letters adapted to be assembled on opposite sides of said element to provide each side thereof with a caution indication, means for securing said letters in position, audible and visual signaling devices mounted at the lower portion of said element for directing attention to said caution indications, and means for illuminating said caution indications, said means arranged at the upper portion of said element.

3. A sign comprising an open frame, a foraminous sheet of material mounted in the opening formed by and secured to the frame and cut away to provide openings, letters adapted to be assembled on opposite sides of said sheet to provide each side thereof with a caution indication, fastening means for securing said letters in position, means supported from the frame and spaced from said letters for illuminating said caution indications, and signaling devices, supported by the frame within said openings for directing attention to said caution indications.

In testimony whereof, I affix my signature hereto.

SAMUEL H. FURRY.
